UNITED STATES PATENT OFFICE.

JIM E. McDERMETT, OF SWENSON, TEXAS.

CARPENTER'S TOOL.

1,294,289.

Specification of Letters Patent. Patented Feb. 11, 1919.

Application filed June 5, 1917. Serial No. 172,983.

To all whom it may concern:

Be it known that I, JIM E. McDERMETT, a citizen of the United States, residing at Swenson, in the county of Stonewall and 5 State of Texas, have invented new and useful Improvements in Carpenters' Tools, of which the following is a specification.

This invention comprehends the provision of an adjustable pattern designed for use by 10 carpenters in determining the exact size and configuration of the space in which a stair tread or riser is adapted to be fitted, so that the material from which the tread or riser is taken, may be properly marked off for 15 cutting with regard to the desired length and angularity at the ends of said parts. Although the device is especially intended for the purpose mentioned, it can be used in other various capacities, such as, in marking 20 off material for the cutting of base boards, rafters, shelving, etc.

The invention aims to provide a device of the above mentioned character which is simple in construction, susceptible of being 25 quickly and easily adjusted to accommodate itself to different angles, and also capable of being folded to provide a compact article when its use is not desired.

The nature and advantages of the invention 30 will be better understood when the following detail description is read in connection with the accompanying drawings, the invention residing in the construction, combination and arrangement of parts as 35 claimed.

In the drawings forming part of this application like numerals of reference indicate similar parts in the several views and wherein:—

40 Figure 1 is a front elevation of the device showing one position of the parts.

Fig. 2 is a rear elevation showing the component parts in a different adjusted position.

45 Fig. 3 is a sectional view on line 3—3 of Fig. 1.

Fig. 4 is a sectional view taken on line 4—4 of Fig. 1.

50 Fig. 5 is a plan view showing the device folded.

Fig. 6 is a cross sectional view taken on the line 6—6 of Fig. 1.

The device forming the subject matter of my invention embodies a cross bar indicated generally at A and consists of two sections 55 10 and 11 respectively. The sections are disposed in the same plane, being arranged end to end, while each section at the rear side is formed with a longitudinally extending groove 13, which groove opens at the adjacent extremities of the respective sections. Received within the grooves 13 and bridging the joint between the respective sections of the bar, is an intermediate section 14. Upon inspection of Fig. 3 of the drawings 60 65 it will be noted that the grooves 13 are of substantially channel-like formation, while the section 14 is formed with a relatively wide base 15 which is disposed beneath the flanges 16 defined by the grooves 13 of the 70 sections 10 and 11, and consequently these parts are interfitted for relative sliding adjustment and are maintained properly associated. Due to this construction and arrangement of parts, it is obvious that the 75 bar A can be readily and easily increased or decreased any length as the occasion may require, and when the proper length has been obtained, the sections 10 and 11 are held fixed relatively and also with respect 80 to the section 14, through the instrumentality of thumb screws 17 carried by the sections 10 and 11 and adapted to engage the intermediate section 14 as shown. Each of the sections 10 and 11 respectively, is provided 85 with a longitudinally extending slot 18 disposed in parallelism with the groove 13, the slot extending throughout the major portion of the length of its respective section. The rear side of each section is also 90 provided with a groove 19 with which the slot 18 communicates. Arranged to slide within the slot 18 of each section is a thumb screw 20 carried by one extremity of a brace 21, the opposite extremity of the latter being 95 secured to an arm 22 associated with said section of the bar for swinging movement. Fitted between the opposed walls of the groove 19 of each section, is a nut 23 with 100 which the thumb screw 20 is associated, so

11/11

that when the arm 22 has been adjusted to the desired position, the thumb screw is rotated in the proper direction to maintain the arm against further adjustment, the thumb screw 20 and nut 23 coöperating for this purpose as will be readily understood. Of course, as the nut 23 is associated with the thumb screw 20, these parts slide within the slot 18 as a unit, but by reason of the fact that the nut is fitted between the opposed walls of the groove 19, turning of the nut with the thumb screw is obviated.

The arms 22 are connected with their respective sections through the instrumentality of links 24 and 25, these links projecting from the opposite sides of each arm and embracing the adjacent end of its respective section, the links being associated with the latter by means of a threaded bolt 26 which passes through said section, and the slots of the links 24 and 25, a nut 27 being associated with the bolt to prevent casual separation of the latter from said section. This construction and arrangement manifestly provides for the swinging of the arms 22 toward and away from each other to assume different angular positions with respect to their associated section, each arm and the adjacent section being beveled as shown to also permit of the adjustment of said arm in the manner stated.

The link 24 of each arm is slightly longer than the link 25 thereof, and passing through the slot in the link 24 in addition to the bolt 26 is a bolt 28. The additional length of the link 24 is necessitated by the provision of this bolt in order that the slot in the link 24 will extend beyond the bolt 28 as far as the slot in the link 25 extends beyond the bolt 26. The bolt 28 is received within an arcuate shaped groove 29 formed in each section 10 and 11, while positioned within each groove 29 is the head 30 of the bolt 28. A nut is threaded upon the bolt 28 to assist in holding the arm 22 in a folded position when use of the device is not desired. By reason of the provision of the slot 29, coupled with the fact that the outer ends of the respective sections are beveled, it is manifest that by loosening the bolt 28, the arms 22 can be swung inwardly and arranged against one edge of its respective section in parallelism therewith. During this adjustment of the arm, the bolt 28 is moved toward one end of the groove 29, and subsequent to the folding of the arms in the manner shown in Fig. 5, the nuts on the bolts 28 are tightened, to hold the arms fixed in their folded position. In this manner a very compact device may be produced to occupy but a minimum of space in a tool box or the like.

In practice, the bar A is arranged within the space to receive the said tread or riser, with a view to determining the size and con-

figuration necessary for the tread or riser to be made to fit the space. The section of the bar can be readily and quickly adjusted to vary the length of the bar as a unit, and the sections held fixed relatively in their adjusted position by tightening the thumb screws 17. The arm 22 can then be independently adjusted to accommodate themselves to a variety of angles at either end, and the arms maintained in their adjusted positions by tightening the thumb screws 20. The device can then be removed and laid upon a board or other material, whereby the said board or material may be properly marked off to indicate the lines upon which the material must be cut in the production of the tread or riser. It is of course to be understood that the device is adapted for use in various capacities for the marking off of material for the production of articles of different characters, such as base boards, shelving or the like.

While it is believed that from the foregoing description the nature and advantages of the invention will be readily apparent, I desire to have it understood that what is herein shown and described constitutes the preferred embodiment of the invention to which I do not limit myself, and that such changes may be resorted to when desired as fall within the scope of what is claimed.

What is claimed is:—

1. A device of the character described comprising a bar, a pair of links pivotally and slidably connected with each of the ends of said bar, an arm pivotally connected between each pair of links, and a brace pivotally connected with each arm and slidably and pivotally connected with said bar.

2. A device of the character described comprising a bar made up of a plurality of relatively slidable sections to vary the length of the bar, means for holding said sections fixed relatively in their adjusted position, arms connected with the opposite ends of the bar to assume different angular positions with respect thereto, a brace pivoted upon each arm and longitudinally and slidably adjustable in relation to the adjacent section of the bar, and means for preventing movement of the brace with respect to said section whereby said arm is held fixed in adjusted position.

3. A device of the character described comprising a bar, having its ends cut at an incline to its length, a pair of links slidably and pivotally connected with each end of said bar, an arm pivotally connected between each pair of links, and a brace pivotally connected with each arm and slidably connected with said bar, the end of said arm adjacent said bar being cut at an inclination to its length to coöperatively engage with

the inclined end of said bar whereby said arm will extend at a definite angle to said bar.

4. A device of the character described comprising a bar, a pair of slotted links disposed upon opposite sides of each end thereof, a bolt extending through said bar and through said slotted links, said bar being provided with an arcuate slot concentric

with said bolt, and an adjusting bolt extending through said arcuate slot and through the slot in one of the links, an arm pivotally connected to and extending between said links, and a brace pivotally connected with said arm and slidably connected with said bar.

In testimony whereof I affix my signature.

JIM E. McDERMETT.
